United States Patent

Des. 237,448
Patented Nov. 4, 1975

237,448

WASHBOARD

William V. Sunday, 9904 Manor Ave.,
Cleveland, Ohio 44104

Filed Apr. 8, 1974, Ser. No. 458,542

Term of patent 14 years

Int. Cl. D7—05

U.S. Cl. D7—201

FIG.1

FIG.2

FIG.3

FIG.4

FIG.5

FIG. 1 is a front perspective view of a washboard showing my new design;

FIG. 2 is a perspective view thereof;

FIG. 3 is a side elevational view thereof, the opposite side being identical thereto;

FIG. 4 is a top plan view thereof; and

FIG. 5 is a bottom plan view thereof.

I claim:

The ornamental design for a washboard, as shown.
